UNITED STATES PATENT OFFICE

WERNER SCHIRMER, OF LEIPZIG, GERMANY, ASSIGNOR TO RUD SACK, OF LEIPZIG, GERMANY

AGRICULTURAL IMPLEMENT

Application filed July 15, 1930, Serial No. 468,021, and in Germany April 18, 1929.

I have filed applications in Germany April 18, 1929; in Czechoslovakia June 7, 1930, and in France June 10, 1930.

My invention relates to agricultural implements and more particularly to means adapted to the frames of such implements for connecting thereto tools such as plough shares.

It is an object of my invention to provide improved means for connecting such tools with the frame.

To this end I arrange in combination means adapted to absorb torsional, and means adapted to absorb bending stress for supporting such tools.

My invention will be described and illustrated as adapted to a plough. In ploughs as in any other agricultural implements low weight is important as such implements must often be transported and obviously the tractive effort required is increased, and the facility of handling the implement is reduced, as the weight increases.

By providing the combined torsion and bending means aforesaid, the strength of the construction is increased very much without unduly increasing its weight.

In the drawing affixed to this specification and forming part thereof part of a plough frame to which my invention has been adapted is illustrated diagrammatically by way of example.

In the drawing

Fig. 1 is an elevation,
Fig. 2 is a plan view of the frame, and
Fig. 3 is a section on the line 3—3 in Fig. 2.

Referring now to the drawing, *a* are three parallel bars of the frame which are connected by suitable transverse stays *h*. *b* is a tubular brace which is arranged above the bars *a* at an angle to the fore- and aft-direction, and *c* are parts resembling gusset plates which are welded or otherwise secured to the tube *b* by means of lugs *f* and *g* which engage the tube at opposite sides. The body of each plate *c* is arranged in parallel with the adjacent bar *a* and secured thereto, as shown in dotted lines in Fig. 2. Each bar *a* is curved to the rear at *i*, as shown in dotted

lines in Fig. 1. The curved portion is riveted or otherwise connected to the adjacent gusset plate *c* and with its lower end projects beyond the gusset plate *c* for supporting the share *d*. A vertical brace *e* extends from the tube *g* to a point near the lower end of the curved part *i* of each bar.

It will appear that each gusset plate *c*, with its brace *e*, and the tube *b*, make up a sort of lattice work which braces the system against lateral deformation without unduly increasing its weight.

The resistance acting on each share exerts thereon a pressure which as indicated at *W* in Fig. 2 is substantially horizontal and inclined at an acute angle to the fore- and aft-direction of the plough. The pressure *W* is split up into two components *W*₁ and *W*₂, the component *W*₁ extending in parallel to the fore- and aft-direction and the component *W*₂ extending at right angles thereto. It is very difficult to brace the frame against these two components without unduly increasing its weight. The stresses resulting from the component *W*₁ can easily be taken care of by providing sectioned bars *a* as shown, or bars of rectangular cross section set on edge but sections which are suitable in this respect are weak against torsion and therefore must be made very heavy in order to absorb the torque resulting from the component *W*₂.

The problem of providing sufficient strength against both components is solved by the lattice-work construction according to my invention. The plates *c* and the braces *e*, being welded to the tube *b* transmit to such tube the torque from the component *W*₂. The tube combines high torsional strength with low weight. By securing the lugs *f* and *g* at the upper end of each plate *c* to opposite sides of the tube *b* the stresses resulting from the component *W*₁ are also partly transmitted to the tube and by these means the plough frame is relieved of stress at the points where such stress might deform it.

I wish it to be understood that I do not desire to be limited to the exact details of construction shown and described for ob-

vious modifications will occur to a person skilled in the art.

In the claims affixed to this specification no selection of any particular modification of the invention is intended to the exclusion of other modifications thereof and the right to subsequently make claim to any modification not covered by these claims is expressly reserved.

10 I claim:—

1. In a frame for an agricultural implement, the combination of a plurality of spaced beams, ground-working tools supported by said beams, a transversely positioned torsional member connected to said beams, a gusset plate connected to each beam at one end and having lugs at its other end for engaging opposite sides of said torsional member, and bracing means connecting each of

20 said tools to said torsional member.

2. In a frame for an agricultural implement, the combination of a plurality of spaced beams, ground-working tools supported by said beams, a transversely positioned torsional member connected to said beams, a gusset plate connected to each beam at one end and having lugs at its other end for engaging opposite sides of said torsional member, and braces each secured to said torsional mem- 30 ber at one end and to a respective tool at the other end.

In testimony whereof I affix my signature.
WERNER SCHIRMER.
